George W. Cleveland, Baltimore Maryland
Letters Patent.

The Vehicle referred to in these Letters Patent and making part of the same, consists of a description in the words of the said George W. Cleveland himself of his improvement in the self adapting Rail Road Car.

To all whom it may concern. Greeting. Know Ye that I George W. Cleveland of the City of Baltimore in the State of Maryland have invented a new and useful improvement in the running gear of Rail Road Carriage and the following is a full and complete description of the construction and operation thereof. The wheels used with my improvement or invention have a perfectly horizontal ^{surface} bearing ^{or} head. The conical shape as now in common use being entirely dispensed with and instead of an outside axle with a wheel fast at each end as now used. I divide the axle into two equal parts with inner or central bearing as hereinafter described and thus leave the wheels to run independently of each other. I connect the same axles at their inner or central bearings, in the following manner. I make a center perch part or carriage frame as represented by A A in fig 1 of the annexed drawings for the inner or central bearings of the same, and connect them by means of a box consisting of two plates of cast or wrought iron or other material, an upper and ^{an} under one, each nine inches in width by two inches in length one on top and one in the back of cast iron, and half an inch thick, the other of wrought iron. The plates, then made apart and connected together and fastened to the center perch by means of four screw bolts passing respectively through the corners of the plates and the center perch. The distance of three inches between the plates being passed by means of four thumb bolts each three inches long, through which the four screw bolts pass between the respective corners of the plates. Or the under plate may be made with solid sides instead of the thumb & screw bolts. In each of the plates and corresponding to each other above and below I make two mortises, as exhibited in Fig. 1. on the draught of the plate B B, each mortise being one inch wide and of a length proportionate to the distance between the wheels, four and a half. or in other words

to the amount of vibration that may be necessary to enable the wheels to conform to the direction of the shafts. These journals are now shaped the arc of a circle, having the semi-axes for a radius and for its centre, ^{the} centre of the revolving box of the outer journal of one of the shafts described. When this box has been constructed, place two vibrating Boxes which are simply two vertical pieces of cast iron on other metal. These boxes, now or left, in length, breadth and thickness, with two flanges on each, one above and one below, on the inner sides to work in the notches in the plates, and corresponding notches in shape and acting as guides in the vibrations of the semi-axes. Through the centre of these vibrating boxes, in the direction of the semi-axes, I make holes of sufficient size to receive the inner journals of the semi-axes, which are turned down to a diameter of one and a half inch more or less leaving shoulders of three-fourths of an inch to work against the vibrating boxes and prevent the semi-axes from sliding to the centre. The journals of the semi-axes pass an inch and a half into the vibrating Boxes so far that it is secure but not so far as to interfere with the balls on the ends of the short lever mentioned hereinafter described. The short Lever which may be of iron or other metal, is made six inches in length more or less according to the distance between the vibrating Boxes, and of an oval shape with a ball turned on each end of a diameter equal to that of the inner journals of the semi-axes, leaving necks sufficiently small to permit the boxes to vibrate, without impinging upon the necks. The first lever works on an axis, passing through its centre, and into the centres of the upper and under plates. This axis may be a screw bolt passing through the centre of the centre Box, and the centre perch and driving a fastening handle. The balls pass into the holes of the vibrating boxes, their shafts di-
ameter and work therein regulating the vibration, by causing them to cor-
respond in distance and thereby preserving the parallelism of the wheels. The vibrating boxes may be made to slide over friction rollers fixed in the upper plate if preferred. The Boxes in which the outer journals of the semi-axes work are constructed in the usual manner except in that in the upper or bearing plate of each box I make a circular depres-
sion or bed of a diameter equal to the circular revolving Box
and

a depth equal to half the thickness thereof. And in the cap piece Sonaka a depression is made to correspond to that of the bearing plates. The revolving box is made circular form and therefore this makes more axles in diameter and two inches more left in thickness exclusive of the housing groove of the outer journal of the semi-axle to work in, and is sunk one inch more axles, into the plate and cap of the box. The groove corresponding in size to the journal of the semi-axle extends throughout the diameter of the revolving box and embraces one half the journal, and instead of depending on the outer side of the box to prevent the axle from sliding outwards, shoulders may be left on the axles to work against the sides of the revolving boxes, and thus prevent sliding outwards. This improvement in invention will allow the wheels of a car to run on the outside of the rails as well as the inside, and always to conform to the course of the Rail way. What I claim as my original invention and never known to me before is the centre block containing the revolving boxes, and pivot lever which connect the inner bearings of the semi-axle and preserve and maintain the parallelism of the wheels and also the inner revolving box within the outer box, which permits the semi-axle at the inner bearing as the same are relatively immobile and explained by the foregoing Specification and the associated drawings, in whatever manner they may be construed so that by means of the same principles of action the vibration of the semi-axle at this inner or centre bearing may be caused and regulated so as to preserve the parallelism of the wheels and permit them by means of their flanches to conform to the course of the Rail way.
